OUTLET TROUGH AND MANDREL BAR ARRANGEMENT FOR TUBE-PIERCING MILLS

George J. Kirchner, Mount Lebanon, Pa., assignor to National Tube Company, a corporation of New Jersey

Application December 18, 1943, Serial No. 514,846

4 Claims. (Cl. 80—13)

This invention relates to a piercing mill for manufacturing seamless tubes and the like, and particularly, to an improved outlet trough and mandrel bar therefor.

In the manufacture of seamless tubes by the Mannesmann or Steifel process, a helical motion is imparted to the billet or workpiece by the rolls of the mill rotating it on its axis and at the same time advancing it over a mandrel arranged in a horizontally disposed outlet trough on the delivery side of the rolls. The forward end of the mandrel carries a piercing point or plug while the rear end is attached to a thrust spindle which permits the mandrel to rotate in the trough with the advancing billet or workpiece.

The purpose of the outlet trough is to receive the pierced billet as it emerges from the piercing mill, to support the billet and mandrel bar in longitudinal alignment during rotary emission of the billet from the mill, to provide suitable mandrel bar thrust resistance and permit rotation by means of a mandrel bar thrust bearing, and to provide means for withdrawing the mandrel bar from the pierced billet at conclusion of the piercing operation and return the mandrel bar to piercing position for the succeeding billet.

Conventional or existing outlet troughs are designed so as to provide for the production of ordinary tubular sections of relatively light wall, comparatively large inside diameters and commercially practical lengths varying from 25 to 50 feet. Such arrangements constitute a mandrel bar of sufficient diameter and of sufficient strength in column to resist any buckling action resulting from the thrust of billet in the piercing operation. In most designs one or possibly two mandrel bar steadiers are applied to reduce effective column lengths of said mandrel bar, and thereby permit the use of lighter mandrels without buckling or undue whipping.

It is evident that the piercing of extremely small inside diameter, heavy wall tubes with such equipment would be a physical impossibility in view of the small diameter mandrel required and subsequent lack of mandrel bar steadyng or "anti-buckling" equipment provided in the existing equipment.

Accordingly, it is the general object of the present invention to provide an outlet trough for accommodating a relatively small diameter mandrel bar whereby the same is rigidly and securely supported and guided so as to prevent buckling or excessive whipping of the mandrel bar so that small diameter seamless tubes and pipe can be conveniently manufactured.

It is another object of the invention to provide an improved outlet trough for tube piercing mills which can be easily and conveniently incorporated and used with existing equipment.

It is a more specific object of the invention to provide an auxiliary outlet trough for tube piercing mills having means carried thereby for supporting the mandrel bar at spaced points substantially throughout the length thereof which in one position supports and guides the mandrel bar and in another position assumes a retracted position away therefrom so as to permit the billet or workpiece to pass freely over the mandrel bar to pierce the same with the supporting means being responsive to the movement of the billet into and through the trough.

It is a further object of the present invention to provide a relatively small diameter mandrel bar complete with an improved thrust bearing arrangement which can be conveniently attached to a larger or conventional mandrel bar and conveniently used with the improved trough of my invention.

Various other objects and advantages of this invention will be more apparent in the course of the following specification and will be particularly pointed out in the appended claims.

In the accompanying drawings there is shown, for the purpose of illustration, an embodiment which my invention may assume in practice.

In these drawings:

Figure 1 is a plan view of the improved outlet trough of my invention;

Figure 2 is a sectional view taken on line II—II of Figure 1;

Figure 3 is a sectional view taken on line III—III of Figure 1;

Figure 4 is a sectional view taken on line IV—IV of Figure 1;

Figure 5 is a sectional view taken on line V—V of Figure 4;

Figure 6 is an enlarged plan view of the rear or thrust block end of my improved outlet trough with the top removed showing the mandrel bar disposed therein together with the supporting members in their protracted position for supporting the same;

Figure 7 is a sectional view taken on line VI—VI of Figure 6;

Figure 8 is a plan view similar to Figure 6 showing the mandrel bar and the billet being pierced in position therein;

Figure 9 is a side view of Figure 8; and

Figures 10 and 10^a are longitudinal sectional views through the improved mandrel bar thrust bearing arrangement of my invention which is adapted to be used with my improved outlet trough wherein the lines X—X represent the line of juncture of the two figures.

The present invention comprises an auxiliary outlet trough, complete with auxiliary mandrel bar thrust block, mandrel bar steadier, pierced billet kickout, and billet stripping equipment for successfully piercing tubes of extremely small

inside diameters and heavy walls with the trough, thrust block, bar steady and kickout equipment being adaptable to outlet trough facilities of existing or conventional piercing mills and utilizing the mandrel withdrawing and returning facilities of such existing or conventional piercing mill outlet troughs.

Referring more particularly to Figures 1 through 9 of the drawings, the improved outlet trough of my invention comprises a longitudinally extending body member 2 having a bottom wall 3, side walls 4 and a removable top wall 5 so as to provide an open ended box-like structure. As more clearly shown in Figures 2 and 3 of the drawings, the body member is supported preferably on a plurality of spaced apart adapters or brackets 6 which are adapted to fit on and be secured to the base sections 7 of a conventional type of outlet trough of existing piercing mills. There are arranged within the body member 2 on the inner sides of the bottom, top and side walls thereof, removable shims or filler members 8 of the proper thickness to provide proper clearance for the outside diameter of the billet B to be pierced as it passes therethrough and which are adapted to guide and support the same in a manner hereinafter to be described. The shims may be attached to the walls of the body member by means of cap screws or any other suitable attaching means so that the shims can be conveniently moved therefrom in case it is desired to replace the same with smaller or larger size shims for piercing different size billets.

There is carried by the removable top 5 and extending to one side thereof, a plurality of outwardly extending arm-like members 9, two in the present instance, which are pivotally attached intermediate the length thereof by means of pins 12 to bosses 10 arranged on the outer side wall of the body member 2, as shown in Figures 1, 3 and 4. There is attached to the extreme outer end of each of the arms 9, preferably a vertically disposed pneumatic cylinder 13, the piston 14 of which is attached to the outer end of the arm by means of a pin 15. The pneumatic cylinder is attached preferably to the base 7 of the existing trough by means of a suitable bracket 16.

At spaced apart intervals throughout the length of the body member 2, there are arranged in the side walls 4 thereof, pairs of rectangular-shaped openings 17 with the opening of each pair positioned directly opposite the other. As more clearly shown in Figure 4 of the drawings, there is arranged in each of the rectangular-shaped openings 17, a mandrel bar steady or supporting finger-like member 18 which is slightly smaller in size than the rectangular-shaped opening so as to provide sufficient clearance therearound. There is arranged in the outer end of each of the members 18, preferably a rectangular-shaped open slot 19 in which there is disposed a removable insert member 20 which is held therein preferably by a pair of cap screws 21. In the outer sides of each of the insert members centrally thereof, there is arranged a semi-circular groove 22 which conforms substantially to part of a diameter of the mandrel bar which is adapted to be used with the trough. In other words, the groove 22 is of such concavity for close guidance of the mandrel bar and insert members 20 are quickly and conveniently replaced for any change of bar size or renewal of worn-out inserts.

Each of the members 18 is preferably attached to the body member 2 at the forward end of the

respective opening 17, preferably by means of a vertically disposed shaft 23 which extends down through the side wall 4 of the body member. The upper end of each of the shafts 23 is cylindrical in shape and journaled in a suitable bearing portion 24 arranged in the upper portion of the side wall. The part of each of the shafts 23 that passes through the members 18 is preferably square or otherwise suitably designed so as to be attached thereto whereby the members 18 rotate when the shafts are rotated. The lower end of each of the shafts 23 is, preferably cylindrical and journaled in a suitable bearing portion 25 arranged in the lower portion of the side wall. The thickness of the members 18 and portions of the shafts 23 are such that when arcuate movement toward the center line of the trough has brought the members 18 at right angles to the center line, as shown in Figure 5, the inner face of the members will bear against the adjacent slot end, thus restricting any further movement in that direction.

Each of the shafts 23 is of sufficient length so as to extend below the bottom of the body member 2, and these extending portions 26 preferably are square and there is attached to each of them, an outwardly extending lug-like member 27 having a slotted opening 28 arranged in the outer end thereof so as to provide substantially a yoke-like portion on the end of each of these members. The members 27 are attached to their respective shafts 23 so that they are disposed at substantially 45 degrees to the center line of the trough and to their respective members 18 when the members are positioned in their protracted positions, as shown in Figure 5. There is arranged and extending between the members 27 of each pair, preferably a coiled spring 39 with the ends thereof connected to the members 27 preferably by means of cap screws 40 for a purpose later to be described. On either side of the body member 2, there is arranged substantially parallel thereto, a longitudinally extending rod 29 which is disposed in and extends through the slotted openings 28 of the members 27 disposed on either side of the body member. There is arranged along each of the rods 29 at a spaced distance from each of the members 27, a collar 30 which cooperates therewith in a manner and for a purpose hereinafter to be described. The rods 29 are mounted for slidable movement along the body member preferably in spaced apart bearing portions 31 arranged on the side walls. At the outer or rearward end of the body member 2, as more clearly shown in Figures 6 through 9 of the drawings, there is arranged a crosshead arrangement 32 consisting of a shaft 33 having an upwardly extending arm 34 arranged on each end thereof with the upper ends of the arms 34 suitably connected to the outer ends of the respective rods 29. There is also carried by the shaft 33, intermediate the length thereof, an upwardly extending arm 35 with the upper end thereof pivotally connected to the outer end of a piston 36 of a pneumatic cylinder 37 suitably arranged below the body member centrally thereof. The shaft 33 of the crosshead is suitably journaled in bearing portions 38 arranged on the endmost adapter 6.

There is arranged in the bottom wall 3 of the members 2 at spaced apart intervals, a plurality of openings 41, two in the present instance, and there is positioned directly opposite each of these openings, a vertically disposed double-acting pneumatic cylinder 42. Each of the pneumatic

cylinders 42 consists preferably of a cylindrical housing 43 which is securely attached to the bottom of the body member by means of cap screws 44 or by any other suitable means. The piston rod 45 of each of the cylinders is securely attached to the base of the housing 43, as at 46, with a piston 47 securely attached to the upper end of the piston rod. There is disposed over and around the piston rod between the same and the housing 43, a cylinder 48 which is designed to move vertically through the respective openings 41 in the bottom of the body member for the purpose of lifting or kicking out the pierced billets in a manner to be described.

At the extreme rearward or thrust block end of the body member 2, as shown in Figures 6 and 7 of the drawings, there is arranged preferably in vertical slots, a stripper block 49 which is preferably of a welded shape having an open top slot 50 arranged therein for passage of the mandrel bar therethrough. On the inner side of the block 49, there is arranged, preferably a face plate 51 which is preferably angularly arranged or canted from the vertical transverse plane in the direction of the thrust block end of the trough. It is the purpose of the face plate 51 together with the thrust block 49 to strip the pierced billet from the mandrel after the piercing operation.

There is shown in Figures 10 and 10^a of the drawings, an auxiliary thrust bearing and coupling arrangement for attaching a relatively small diameter mandrel bar to the end of a larger size or conventional type mandrel bar which smaller size mandrel bar is adapted to be used with the improved outlet trough of the present invention. The auxiliary thrust bearing comprises a housing or casing 52 having an outer diameter substantially equal to that of the conventional or larger size mandrel bar 53 to which it is attached preferably by means of a threaded connection 54. There is disposed within the housing or casing 52, a rotatable spindle 55 of varying outside diameter. There is arranged on the spindle 55 intermediate the length thereof, an anti-friction thrust bearing 56 with the race thereof which is adapted to rotate therewith pressed on the spindle so as to provide a tight fit and abutting against a shoulder 57 of the spindle. The stationary or opposed race of this bearing abuts against a shoulder 58 arranged on the inner periphery of the housing 52. Adjacent the outer end of the spindle 55, there is arranged an anti-friction radial bearing 59 with the outer race thereof having a tight fit with the internal bore of the casing 52 with the inner race having a tight fit with the spindle and abutting against a shoulder 60 carried thereby. Adjacent the inner end of the spindle 55, there is arranged a smaller anti-friction radial bearing 61 which fits tightly over the spindle and abuts against a shoulder 62 carried thereby. The outer race of the bearing 61 fits tightly around the inner periphery of a smaller diameter portion of the casing 52. There is arranged on a small diameter portion of the spindle 55 directly next to the bearing 61, a spacer 63 so designed to transmit longitudinal force against the inner race of the opposing spindle shoulder 62. The spacer 63 is forced inwardly by means of an adjustable nut 64 arranged on a threaded end portion of the spindle. The spacer 63 and the nut 64 are retained in proper position, preferably by lock washer 65 and lock nut 66. The outer diameter of the spacer 63 is maintained at proper magnitude to insure proper clearance with the end

bore of the casing 52 in which annular V-shaped grooves or any other suitable means is provided for establishing a seal between rotating and stationary parts. It will be understood, that the internal bore of the casing 52 at the thrust bearing zone, that is, at the bearing 56, is in excess of the outer diameter of this bearing so as to insure perfect spindle alignment with respect to the anti-friction radial bearings 59 and 61.

10 Adjacent the outer end of the spindle 55, there is threaded into the outer end of the casing 52, a collar retaining member or plug 67 which is provided so as to exert pressure against the inner race of the bearing 59 which pressure is transmitted to the spindle 55 and to the spindle shoulder 60 and thence to the spindle shoulder 57 to the thrust bearing 56, which pressure is resisted by the internal shoulder 58 of the casing 52. When the proper pressure has been applied 15 by the retainer 67 by tightening the same, such pressure or assembly tightness is maintained preferably by a plug or set screw 68 arranged in the periphery of the casing 52 and extending into a hole 69 arranged in the periphery of the retainer 67. The internal bore of the retainer nut 67 is provided with sufficient clearance with the spindle 55 and there are provided preferably annular V-grooves or any other suitable means for establishing a seal between the rotating and stationary parts at this end of the casing. By providing such a construction, it will be seen that any lost motion between the bearing elements of the assembly is eliminated and, should the parts wear, it will be seen the retainer nut 67 can be tightened to compensate for such wear so as to again provide a relatively tight assembly.

On the extreme outer end of the spindle 55, there is arranged a mating portion 70 for flexible juncture with the complementary mating half 71 arranged on the inner end of the small diameter mandrel bar 72. The mating portions 70 and 71 preferably have spherically radiused or concave-convex mating surfaces, as at 73, so as to provide a flexible connection, but it will be understood that any other suitable connection may be provided at this point. There is provided a split coupling 74 for holding the mating portions 70 and 71 in engagement with each other, and at the same time to permit limited movement of the mandrel bar 72 relative to the spindle 55. The external profile and diameter of the coupling 74 is such as to offer no interference with conventional mandrel guiding equipment during longitudinal movement of the mandrel in either direction during mandrel withdrawing or advancing operations. In other words, the coupling 74 has a smooth outer contour and is preferably frusto-conical shaped with the largest diameter thereof being substantially equal to the outer diameter of the casing 52.

It will be understood that the small diameter mandrel bar 72 is of sufficient length to extend completely through the outlet trough so as to position the piercing point or plug 75 arranged on the outer end thereof at proper piercing position in the piercing mill. The spindle is preferably axially bored as at 76, and there is arranged therein and extending therethrough a longitudinally extending small diameter water cooling pipe 77 which extends into and through the mandrel bar 72 and terminates adjacent the outer end of the piercing point or plug 75. The water cooling pipe 77 is of such diameter as to provide sufficient clearance between the outer sides thereof and the inner bore of the spindle

and the mandrel bar so as to provide sufficient clearance therebetween for permitting a return flow of the water from the piercing point in a well known manner. The inner end of the water cooling pipe 77 is connected preferably to the end of the conventional or larger size water cooling pipe 78 arranged in the mandrel 53 by means of a reducing coupling 79.

The improved trough of my invention, together with the auxiliary thrust bar bearing assembly functions in the following manner. It will be understood that the auxiliary trough of the present invention is first assembled in position on the base of or in a conventional or larger size trough by means of the adapters 6 and that the small diameter mandrel bar 72 is attached to the end of the conventional or larger type mandrel bar 53 by means of the thrust bearing assembly hereinafter described.

It will be assumed that the fingers or mandrel bar supporting members 18 of the trough are disposed in their respective openings 17 in the side walls of the body member, and in position substantially parallel to the center line of the trough, as shown in Figures 1 and 2 of the drawings, with the auxiliary mandrel bar 72 positioned at the outer end thereof ready to be brought forward toward the mill for the piercing operation. A suitable fluid is then introduced into the pneumatic cylinder 37 by any suitable connection and means, and the piston thereof is moved thereby toward the outer or thrust block end of the trough which, in turn, moves the two rods 29 disposed on either side of the trough in the same direction or longitudinally through the action of the cross-head arrangement 32 which is arcuately rotated by means of the pneumatic cylinder. As the rods 29 move, it will be seen that the collars 30 carried thereby also move and abut against the lug-like members 27 arranged on the shafts 23, thereby imparting a turning movement thereto. Upon such turning movement of the shafts 23, it will be seen that the members 18 attached or keyed thereto are moved outwardly to their protracted positions within the trough so as to extend therewith, as shown in Figures 6 and 7 of the drawings. It will be understood that after the arcuate movement of the fingers or members 18 has exceeded 45 degrees, the tension springs 39 effect completion of a total movement of 90 degrees. As hereinbefore explained, the members 18 are arranged in the slots 17 so that when they are moved to their right-angular position or protracted positions, the sides of each of the members 18 abut against the adjacent vertical end walls of their respective openings 17 so as to limit the inward movement of these members. In other words, the springs 39 complete the movement of the members 18 so as to position and maintain the same against the vertical end walls of the openings 17 which act as stops for such movement of these members. A suitable fluid is then introduced into the opposite end of the cylinder 37 so that it is actuated in the reverse direction whereby the rods 29 together with the collars 30 carried thereby are moved to their original positions with the collars 30 in such position adapted to act as stops for the members 27 upon movement of the supporting members 18 to their original position or retracted position in the side walls, in a manner hereinafter to be described.

The outlet trough is now in readiness to receive the mandrel bar 72 for the piercing operation. The auxiliary or smaller diameter mandrel bar

72 is then moved forward into and through the trough by means of conventional equipment which usually consists of a sheave cable arrangement which operates a conventional thrust carriage in a manner well known to those skilled in the art. As the mandrel bar 72 passes into the trough, it passes into and through the cylindrical openings formed by the semi-circular grooves 22 arranged in the opposed ends of the insert members 20 carried by each pair of fingers or supporting members 18. The outer or mandrel entry side of each of the semi-circular grooves 22 of the insert members is preferably beveled or flared as at 80 so as to aid in guiding and directing the mandrel bar therethrough.

After the mandrel bar has passed entirely into the trough and is disposed therein, it will be understood that the piercing point or plug 75 is properly positioned in the piercing mill for piercing a billet in the conventional manner. It will be seen that the supporting members 18, together with the inserts 20, carried thereby, support the mandrel bar 72 at spaced apart points throughout the length thereof. The thrust carriage is then locked by the conventional mechanism so as to preclude any movement of the mandrel bar as a result of the thrust to which it is subjected during the piercing operation. A cylindrical billet B is then introduced into the piercing mill and passes therefrom over the piercing point 75 and the mandrel 72 into and through the trough. As the billet advances, it is helically rotated with consequent mandrel and auxiliary mandrel bar rotation in combination with longitudinal thrust 35 which is resisted by the thrust bearing assembly and the latching mechanism. As the billet passes over the mandrel bar, it will be seen that the insert members 20, together with the members 18 to which they are attached, reduce the effective 40 column length of the mandrel bar thereby steady- 45 ing the same and thus precluding any buckling action due to the aforementioned thrust.

As the pierced billet passes through the outlet trough, each pair of fingers 18 together with the inserts 20 carried thereby are successively forcibly displaced as the leading end of the billet comes into contact therewith, as shown in Figures 8 and 9 of the drawings, thereby moving the same about their pivotal connections at the shafts 23 and 50 rotating the same. When the arcuate magnitude of the displacement of the members 18 exceeds 45 degrees, the tension springs 39 will act to effect completion of a 90 degree movement thereof so as to complete the movement of the members 18 and return the same to their retracted positions 55 within their respective openings 17 in the side walls of the body member. When the members 18 have been returned to their fully retracted positions within their respective openings 17 and are 60 disposed substantially parallel to the mandrel bar or the center line of the trough, it will be understood that the outer ends of the lug-like members 27 will abut against their respective collars 30 on the rods 29 which act as stops so as to prevent further outward movement of the members 18. As the billet passes through the trough and over the mandrel bar therein, it will be seen that the shims 8 arranged on the inner walls of the trough act to guide and support the billet as it passes therethrough.

After the billet has been completely pierced and has moved into the trough substantially the full length thereof, and all of the supporting members 18 have been moved to their retracted positions, the piercing operation is completed and the

billet is ready to be removed from its position in the trough. The mandrel latching mechanism is then released and the sheave-cable arrangement is actuated in a direction opposite that for positioning the mandrel bar in the trough and the piercing mill thereby moving the thrust bearing mandrel bar assembly away from the mill and consequently the mandrel out of the trough. As the mandrel moves from the trough, the leading end of the pierced billet B strikes the canted face of the face plate 51 of the stripper block 49, thereby permitting the mandrel bar to be withdrawn therefrom. It will be seen that the canted face of the plate 51 precludes subsequent adhesion of the hot pierced billet to the stripper block.

After the mandrel has been removed from the trough, the top 5 is removed by actuating of the pneumatic cylinders 13 so as to permit removal of the pierced billet from within the trough. The pneumatic kick-out cylinders 42 are then actuated so as to lift and move the pierced billet upwardly from the trough through the top thereof to a position thereabove. The billet is then pushed off the upper ends of the pistons of the pneumatic cylinders 42 preferably onto a skid arrangement S arranged along one side of the trough, as shown in Figure 3, over which they roll and pass to the next operation.

As a result of my invention, it will be seen that there is provided an auxiliary outlet trough and small diameter mandrel bar together with a thrust bearing arrangement, which can be used and conveniently incorporated with conventional piercing mill equipment.

It will be seen also that the improved outlet trough of the present invention rigidly supports the mandrel bar during the piercing operation, thereby eliminating any excessive vibration or buckling thereof, and, at the same time, does not interfere with conventional piercing operations.

While I have shown and described one specific embodiment of my invention, it will be understood that this embodiment is merely for the purpose of illustration and description and that various other forms may be devised within the scope of my invention, as defined in the appended claims.

I claim:

1. Apparatus of the class described including, in combination, an auxiliary outlet trough for a tube piercing mill, means for attaching said trough to conventional piercing mill equipment, a relatively small diameter auxiliary mandrel bar which is adapted to be used with said trough, means carried by said trough for supporting and guiding the mandrel bar when disposed therein, and means for attaching said small diameter mandrel bar to the end of a larger size mandrel bar of the mill.

2. Apparatus of the class described, as defined in claim 1, where the means for attaching the small diameter mandrel bar to the large mandrel bar consists of a thrust bearing and coupling arrangement.

3. In an outlet trough for a tube piercing mill of the class described including a mandrel bar for supporting a piercer point for piercing billets, a

plurality of spaced apart pairs of members carried by said trough and in one position adapted to extend thereinto for supporting and guiding the mandrel bar when disposed therein at spaced points substantially throughout the length thereof with each member of each of said pairs positioned horizontally on opposed sides of the mandrel bar, means pivotally mounting each of said supporting and guiding members at either side of said trough, arms connected to said pivotally mounted supporting and guiding members which extend outwardly and diagonally therefrom and rearwardly of said trough when said guiding members extend inwardly of said trough in their protracted position and forwardly when said members are in their retracted position, a spring member connecting each pair of oppositely disposed arms for yieldably maintaining each of said supporting members in a protracted position when they extend into said trough for supporting said mandrel bar and for maintaining said members in a retracted position and out of contact with a billet when moved to a retracted position thereby, each pair of mandrel supporting and guiding members adapted to be moved successively out of a protracted position to a retracted position by the billet as it advances therethrough and to be simultaneously returned to a protracted position by means engaging said arms.

4. An outlet trough for tube piercing mills of the class described comprising a longitudinally extending body member having a removable top wall and side and bottom walls so as to provide an open ended box-like structure, guide shoes arranged on the inner side of said top and side and bottom walls for guiding the outer sides of the billet as it passes therethrough, a plurality of spaced apart pairs of mandrel supporting members carried by said body member with each member of each pair positioned directly opposite each other and pivotally mounted in the side walls of said body member, said members adapted to extend into the trough in one position substantially perpendicular to said side walls for supporting and guiding the piercing mandrel bar when disposed therein and in another position adapted to assume a retracted position in said side walls away from the mandrel bar, and means for moving said supporting members to their protracted positions, each pair of said supporting and guiding members adapted to be moved successively out of engagement with the mandrel bar to their retracted position in the side walls of said body member by the billet upon movement of the same into and through said trough so as to permit the billet to pass freely over the mandrel bar to pierce the same whereby the mandrel bar is supported by said pairs of pivotally mounted members when in their protracted position and the telescoped billet is supported by said guide shoes after said billet has moved said pivotally mounted members to their retracted position.
